UNITED STATES PATENT OFFICE.

FRANCIS H. RICHARDS, OF HARTFORD, CONNECTICUT, ASSIGNOR, BY MESNE ASSIGNMENTS, OF ONE-HALF TO AMERICAN TYPOGRAPHIC CORPORATION, A CORPORATION OF NEW JERSEY.

ADDING-MACHINE.

No. 866,162.

Specification of Letters Patent.

Patented Sept. 17, 1907.

Application filed December 20, 1900, Serial No. 40,572. Renewed February 3, 1906. Serial No. 299,298.

To all whom it may concern:

Be it known that I, FRANCIS H. RICHARDS, a citizen of the United States, residing at Hartford, in the county of Hartford and State of Connecticut, have invented 5 certain new and useful Improvements in Adding-Machines, of which the following is a specification.

This invention relates to improvements in adding-machines such as are shown in my Patent No. 590,277, dated September 21, 1897, and has for its principal object 10 the provision of improved driving mechanism and means for controlling the same.

In the accompanying drawings, Figure 1 is a side elevation of an adding-machine embodying my present invention, parts of the casing being broken away. Fig. 15 2 is a transverse vertical section on the line *a—a* of Fig. 1. Fig. 3 is a horizontal section on the line *b—b* of Fig. 1. Fig. 4 is a perspective view of the key levers and bars coöperating therewith. Figs. 5, 6, and 7 are side elevations of a controlling device and its stop in 20 three different positions. Fig. 8 is a top plan view of Fig. 6. Figs. 9, 10, and 11 are, respectively, an end elevation, side elevation and a section of one of the driving-gears showing its frictional connection with the shaft; and Fig. 12 is a sectional detail of a part of the 25 indicating wheel.

Similar characters designate like parts in all the figures of the drawings.

In some suitable casing, designated in a general way by C, may be mounted a short shaft 10 journaled in 30 bearings 11—12, the former on one side thereof and the latter in the web or support 13 cast with or secured to the inside of the casing. This shaft, which is the main driving-shaft, has upon its outer end a pulley 14 by which it may be rotated by the belt from any suitable 35 source of power, and a gear 15 for transmitting this rotation to other elements of the machine.

Preferably journaled with one end in a portion of the bearing 12 and the other in a bearing 16 in the opposite side of the casing is a shaft 17, upon and about which 40 may be supported sets of gearing constituting the driving mechanism or adding train for an indicating mechanism, designated as a whole by A, to be hereinafter described. These sets of gearing preferably consist of uniformly-placed pairs of bevel-gears 18—18', 19—19', 45 and 20—20', all of equal size, which are loose upon the shaft 17, except the outer ones 18 and 20'. The former is held fast upon the shaft 17 and is connected thereby with the indicating mechanism, and the latter is fixed to the casing. Meshing with these pairs of bevel-gears 50 and spacing the intermediate ones apart are bevel-gears 21, 22, and 23, one or more in number but preferably three, and of the same size as 18, 19, 20, each set being mounted at equi-distant points about the inside of equal sized annular spur-gears 21', 22', and 23', in 55 the manner shown in Fig. 19 of the previously men-

tioned patent, or otherwise, to rotate freely, and to revolve orbitally about the shaft 17, supported by the pairs of bevel-gears thereon. The several sets having their corresponding gears of the same size, each to each, constitute, therefore, interchangeable sets of driving 60 mechanism.

Meshing with the gears 21', 22', 23' are spur-gears 24, 25, 26 of equal diameter and fast upon shafts 24', 25', 26', respectively, which extend transversely of the casing and are journaled therein at points equi-distant from the shaft 10. These three shafts each carry a gear 27, all of equal diameter and meshing with the main driving-gear 15. The gears 27 are loose upon their shafts but are given some frictional engagement therewith. This may be effected by placing at one side of the gear 70 a disk 28 fast upon the shaft, and upon the other side a loose ring 29 about a threaded portion upon which are a nut 30 and a lock-nut 31. Between the inner faces of the two disks and the faces of the gear-hub may be interposed washers or rings 29' of any suitable material, 75 fiber, for example. By varying the position of the nuts the frictional engagement of the gears with the shafts may be varied within the desired limits, and they are thus made to turn more or less easily thereon.

As it is desired that the driving mechanisms shall be 80 intermittently actuated and at the will of the operator, a controlling device is provided for each shaft 24', 25', 26', which is here shown as consisting of one or more arms or members projecting from hubs 32 secured thereto. The hub on the first named shaft is provided with 85 four arms designated as 34, the second with two arms 35, and the third with one arm 36. Each arm has at its end a projection 37 at one side thereof, which may be formed by bending over the end of the arm. As a selector for rendering any one of these devices effective, 90 a movable stop or pallet is provided for each, designated as a whole by S, consisting of a hub 38 from which projects an upwardly-extending portion 39 having two steps or contact surfaces, an upper 39' and a lower 39'', formed by projections from one side of the main portion. 95 Each of the stops has its hub secured to a transverse shaft 40 suitably journaled in the casing, their position thereon being such that the projections 39—39'' may be moved in the path of the projections 37 upon the arms, while the latter projections do not extend as far as the portion 39 of the stop.

Upon each of the hubs carrying the stops for the arms 34 and 36 is a lever-arm 41, extending therefrom substantially at 90 degrees with the portion 39 of the stops, with which a rod 42 has pivotal connection at one end, 105 and at the other with one of two selector-bars lying in the lower portion of the casing. The hub carrying the stop for the arms 35, which lies near the rear of the casing, has a lever-arm 41*, which is substantially at 180 degrees from the stop body, and its connecting-rod 41^b 110

is pivoted to the bell-crank lever 41^c turning with a transverse shaft 41^d. This lever has its other arm pivotally connected by the rod 41^e to a third bar. These three bars 44, 45, and 46, which are connected respectively with the stops for the controlling devices 34, 35, and 36 are preferably U-shaped, lying within one another and mounted to turn at their ends about a horizontal shaft 43 extending between the walls of the casing. Preferably also mounted to turn upon the shaft 43 are key-levers L, which rest upon the upper edge of the selector-bars, extending through slots in the front of the casing and carrying keys K, here shown as numbered from 1 to 7. At the point of contact with the bars the lever designated as 1 has a downward projection of such a size and so positioned that this lever touches only the bar 45, while lever 2 is provided with a projection touching only bar 44, lever 3 bars 44 and 45, lever 4 bar 46, lever 5 bars 45 and 46, lever 6 bars 44 and 46, and lever 7 all three bars. Springs 47 secured to the casing and contacting with the under side of the levers may be used to hold them in a normally raised position, while a single heavier spring 48 may serve the same purpose for the selector-bars.

Upon the outside of the casing adjacent to the gear 20^c is mounted some suitable form of indicating device, which may consist of a wheel 49 journaled for rotation and having mounted to turn upon its outer face a flanged ring 49^c with which it is connected by a spring pin 49^b carried by a projection secured to the ring and engaging one of a series of holes in the outer edge of the wheel-rim. The ring bears upon its outer face a number of equal divisions, herein shown as 150, suitably numbered. The wheel 49 is provided with an internal spur-gear 50 meshing with a pinion 51 upon a short shaft journaled in the casing, which has rotating with it a gear 52 in mesh with a gear 53 fast upon the shaft 17 with the bevel-gear 18 of the adding train. A pointer 54 fixed to the casing projects over the divisions on the ring.

40 In the operation of the machine, the main driving shaft being continually rotated by its pulley, the gears 27 are also continually rotated thereby, normally slipping between the disks and holding the projections on the controlling members in contact with the upper face 39^c of the stops, as is shown in Fig. 5. If a key is depressed by the operator—for example, that numbered 1—it will force down the bar 45 and through its connections will move the stop away from one of the four arms 34 sufficiently to permit it to be carried 45 by the rotation of the shaft 24^c into contact with the face 39^b, as it is shown in Fig. 6. Then as the key is released by the operator the springs will press the lever and bar 45 upward again and move the stop back to its former position, the projection on the arm now slipping off the stop face 39^b at its outer edge, as is shown 50 in Fig. 7, and the shaft 24^c rotating until the next of the four arms 24^c contact with the upper stop face. This movement of the shaft, which amounts to a rotation of 90 degrees, will be transmitted through gears 24 and 21^c to the first set of the train of gearing, rotating it with its companion sets about the fixed gear 20^c, which movement will be transmitted to the gear 18 turning the shaft 17 and consequently the indicating device through one division, the intermediate gearing 55 thereof being so proportioned that the movement of

any one of the controlling arms through a quarter turn will move one division upon the ring under the pointer. If instead the key bar 3 had been pressed its projection would have depressed both the bars 44 and 45, releasing the controlling devices for the first and second sets 70 of the driving mechanism constituting the gear train, the four-armed member of the former permitting a quarter turn of the gear 21^c and the two-armed member of the latter a half turn of the gear 22^c. Both these effects will be transmitted to the gear 18, and as a result the indicator will be turned through three divisions. It may be readily seen that the depression of the various other keys will produce similar effects, the selector-bars acted upon causing the release of one or more of the three controlling devices, and consequent 80 movements of the driving mechanisms being permitted through a quarter, a half, or a whole turn, and effecting the indicator either separately or with their movements added to one another, the work done by each of these mechanisms being directly proportional 85 to the angle through which its controlling device turns, or inversely proportional to the number of arms thereof. The machine will thus go on indicating the sum of the figures upon the keys pressed until the highest amount on the ring has reached the pointer, when the 90 scale will again move under it. If the sum of the figures added amounts to less than the highest indication, the ring may be brought back under the pointer for another operation by withdrawing the spring pin from the hole in the wheel and turning the ring back 95 until the pointer is again over the zero mark, when addition may proceed as before.

It will be seen that by so organizing the machine that each controlling device turns through the same angle as the driving mechanism it governs, or, as it 100 may be stated, has a movement proportionate to the work to be done by the associated driving mechanism rather than to allow all to have equal movements and then gearing up to obtain the desired rotation of the driver, two important advantages are gained: First, 105 the friction in the parts while work is being done is substantially proportionate to the amount of said work, so that there will be less wear, diminishing the cost of maintenance, and, second, since the similarly situated or homologous gears of the driving mechanisms 110 and their coaxing elements are of equal diameter, they may be made in sets, each having a number of equal size so that there will be a less variety of parts to construct, thus very greatly diminishing the cost 115 of production.

Having thus described my invention, I claim—

1. The combination of an integrating shaft; indicating mechanism actuatable therefrom, a plurality of interchangeable mechanisms mounted on said shaft and each designed to turn said shaft through a different angle than the other; a separate actuator for each said interchangeable mechanism, said actuators being grouped around the shaft; controllers associated with such actuators for permitting amounts of movement of the actuators directly proportional to the angle through which the respective 120 said mechanisms are designed to turn the integrating shaft.

2. The combination of an integrating shaft; indicating mechanism actuatable therefrom; a plurality of interchangeable mechanisms mounted on said shaft and each designed to turn said shaft through a different angle than the others; a separate actuator for each said interchangeable mechanism, said actuators being grouped around the shaft; and escapements associated with such actuators for 125

permitting amounts of movement of the actuators directly proportional to the angle through which the respective said mechanisms are designed to turn the integrating shaft.

2. The combination of an integrating shaft; indicating mechanism actuatable therefrom; a plurality of interchangeable mechanisms mounted on said shaft and each designed to turn said shaft through a different angle than the others; a separate actuator for each said interchangeable mechanism, said actuators being grouped around the shaft; controllers associated with such actuators for permitting amounts of movement of the actuators directly proportional to the angle through which the respective said mechanisms are designed to turn the integrating shaft; and a driver common to all the actuators.

15 4. The combination of an integrating shaft; indicating mechanism actuatable therefrom; a plurality of interchangeable mechanisms mounted on said shaft and each designed to turn said shaft through a different angle than the others; a separate actuator for each said interchangeable mechanism, said actuators being grouped around the shaft; escapements associated with such actuators for permitting amounts of movement of the actuators directly proportional to the angle through which the respective said mechanisms are designed to turn the integrating shaft; and a driver common to all of the actuators.

20 5. The combination of an integrating shaft; indicating mechanism actuatable therefrom; a plurality of interchangeable mechanisms mounted on said shaft and each designed to turn said shaft through a different angle than the others; a separate actuator for each said interchangeable mechanism, said actuators being grouped around the shaft; escapements associated with such actuators for permitting amounts of movement of the actuators directly proportional to the angle through which the respective said mechanisms are designed to turn the integrating shaft; and a driver common to all of the actuators and from which such actuators are frictionally driven.

25 6. The combination of an integrating shaft; indicating mechanism actuatable therefrom; a plurality of interchangeable mechanisms mounted on said shaft and each designed to turn said shaft through a different angle than the others; a separate actuator for each said interchangeable mechanism, said actuators being grouped around the shaft; escapements associated with such actuators for permitting amounts of movement of the actuators directly proportional to the angle through which the respective mechanisms are designed to turn the integrating shaft; a driver common to all the actuators and from which such actuators are frictionally driven; and means for selectively operating the escapements.

30 7. The combination of an integrating shaft; indicating mechanism actuatable therefrom; a plurality of interchangeable mechanisms mounted on said shaft and each adapted to turn said shaft to a different angle than the others; a separate actuator for each said interchangeable mechanism, said actuators being grouped around the shaft; escapement devices associated with such actuators and each such device comprising a different number of stop-arms than the others; shiftable stop members adapted to 35 co-operate with the stop-arms comprised in the escapement devices; and selective mechanisms.

35 8. The combination of an integrating shaft; indicating mechanism actuatable therefrom; a plurality of interchangeable mechanisms mounted on said shaft and each adapted to turn said shaft through a different angle than the others; a separate actuator for each said interchangeable mechanism, said actuators being grouped around the shaft; escapement devices associated with such actuators and each such device comprising a different number of 40 stop-arms than the others; a driver common to all of said actuators and from which said actuators are frictionally driven; vibratory stop members adapted to co-operate with the stop-arms; and selective mechanism.

45 9. The combination of an integrating shaft; indicating mechanism actuatable therefrom; a plurality of interchangeable gears encircling the shaft; a fixed gear; a gear attached to said shaft; a train of gearing extending from said fixed gear to said gear attached to the shaft and actuatable at different points by said encircling gears; interchangeable actuator gears each meshing with one of said

encircling gears; and controllers for permitting angular movement of the respective actuator gears to an extent dependent upon the extent of movement of the respective encircling gears are designed to have.

10. The combination of an integrating shaft; indicating mechanism actuatable therefrom; a plurality of interchangeable gears encircling the shaft; a fixed gear; a gear attached to said shaft; a train of gearing extending from said fixed gear to said gear attached to the shaft, and actuatable at different points by said encircling gears; interchangeable actuator gears each meshing with one of said encircling gears; and escapements for permitting angular movement of the respective actuator gears to an extent dependent upon the extent of movement of the respective encircling gears are designed to have.

15 11. The combination of an integrating shaft; indicating mechanism actuatable therefrom; a plurality of interchangeable gears encircling the shaft; a fixed gear; a gear attached to said shaft; a train of gearing extending from said fixed gear to said gear attached to the shaft, and actuatable at different points by said encircling gears; interchangeable actuator gears each meshing with one of said encircling gears; and escapements comprising stop-arms the number of which depends on the extent of movement of the respective actuator gears.

20 12. The combination of an integrating shaft; indicating mechanism actuatable therefrom; a plurality of interchangeable gears encircling the shaft; a fixed gear; a gear attached to said shaft; a train of gearing extending from said fixed gear to said gear attached to the shaft, and actuatable at different points by said encircling gears; interchangeable actuator gears each meshing with one of said encircling gears; escapements comprising stop-arms, the number of which depends on the extent of movement of the respective actuator gears; and a driver common to all of said actuator gears.

25 13. The combination of an integrating shaft; indicating mechanism actuatable therefrom; a plurality of interchangeable gears encircling the shaft; a fixed gear; a gear attached to the shaft; a train of gearing extending from said fixed gear to said gear attached to the shaft, and actuatable at different points by said encircling gears; interchangeable actuator gears each meshing with one of said encircling gears; a shaft for each actuator gear; a spur-wheel on each shaft; a driver with which all of said latter gears mesh; and escapements; comprising stop-arms the number of which depends upon the extent of movement of the respective actuator gears.

30 14. The combination of an integrating shaft; indicating mechanism actuatable therefrom; a plurality of frictionally driven interchangeable gears encircling the shaft; a fixed gear; a gear attached to the shaft; a train of gearing extending from said fixed gear to said gear attached to the shaft, and actuatable at different points by said encircling gears; interchangeable actuator gears each meshing with one of said encircling gears; a shaft for each actuator gear; a spur-wheel on each shaft; a driver with which all of said latter gears mesh; and escapements comprising stop-arms the number of which depends upon the extent of movement of the respective actuator gears.

35 15. The combination of an integrating shaft; indicating mechanism actuatable therefrom; a plurality of interchangeable gears encircling the shaft; a fixed gear; a gear attached to said shaft; a train of gearing extending from said fixed gear to said gear attached to the shaft, and actuatable at different points by said encircling gears; interchangeable actuator gears each meshing with one of said encircling gears, escapements comprising stop-arms the number of which depends upon the extent of movement of the respective actuator gears; a driver common to all of said actuator gears; and a driver shaft whose axis is coincident with the axis of the integrating shaft.

40 16. The combination of an integrating shaft; indicating mechanism actuatable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side,

- each of which side gears is affixed to the contiguous side gear of the adjacent encircling gear; interchangeable actuator gears, each meshing with one of said encircling gears; and controlling devices for permitting angular movements of the actuator gears dependent upon the extent of movement the respective encircling gears are designed to have. 5
17. The combination of an integrating shaft; indicating mechanism actuable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side, each of which side gears is affixed to the contiguous side gear 10 of the adjacent encircling gear; interchangeable actuator gears, each meshing with one of said encircling gears; and escapements for permitting angular movements of the actuator gears dependent upon the extent of movement the respective encircling gears are designed to have. 15
18. The combination of an integrating shaft; indicating mechanism actuable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side, each of which side gears is affixed to the contiguous side gear of the adjacent encircling gear; interchangeable actuator gears, each meshing with one of said encircling gears; and escapements comprising stop arms, the number of which depends on the extent of movement of the actuator gears for permitting angular movements of the actuator gears dependent upon the extent of movement the respective encircling gears are designed to have. 20
19. The combination of an integrating shaft; indicating mechanism actuable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side, each of which side gears is affixed to the contiguous side gear of the adjacent encircling gear; interchangeable actuator gears, each meshing with one of said encircling gears; and escapements comprising stop arms, the number of which depends on the extent of movement of the actuator gears for permitting angular movements of the actuator gears dependent upon the extent of movement the respective encircling gears are designed to have, and a common driver for the actuator gears. 25
20. The combination of an integrating shaft; indicating mechanism actuable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side, each of which side gears is affixed to the contiguous side gear of the adjacent encircling gear; interchangeable actuator gears, each meshing with one of said encircling gears; and escapements comprising stop arms, the number of which depends on the extent of movement of the actuator gears for permitting angular movements of the actuator gears dependent upon the extent of movement the respective encircling gears are designed to have, a common driver for the actuator gears, a shaft for each said actuator gear, and a gear wheel on each shaft. 30
21. The combination of an integrating shaft; indicating mechanism actuable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side, each of which side gears is affixed to the contiguous side gear of the adjacent encircling gear; frictionally driven interchangeable actuator gears, each meshing with one of said encircling gears; and escapements comprising stop arms, the number of which depends on the extent of movement of the actuator gears for permitting angular movements of the actuator gears dependent upon the extent of movement the respective encircling gears are designed to have, a common driver for the actuator gears, a shaft for each actuator gear, and a gear wheel on each shaft. 35
22. The combination of an integrating shaft; indicating mechanism actuable therefrom; a plurality of interchangeable gears encircling the shaft; a fixed gear; a gear attached to the shaft; transmitting mechanism for each said encircling gears comprising bevel wheels mounted in the encircling gear and a bevel wheel at each side, each of which side gears is affixed to the contiguous side gear of the adjacent encircling gear; frictionally driven interchangeable actuator gears, each meshing with one of said encircling gears; and escapements comprising stop arms, the number of which depends on the extent of movement of the actuator gears for permitting angular movements of the actuator gears dependent upon the extent of movement the respective encircling gears are designed to have, a common driver for the actuator gears, a shaft for each actuator gear, a gear wheel on each shaft, and a driver shaft whose axis is coincident with the axis of the integrating shaft. 40
